DESIGN FOR EMBOSSED PAPER FOR PAPER NAPKINS OR SIMILAR ARTICLES

Ruth E. Gutfrucht, Rochester, N. Y., assignor to Sherman Paper Products Corporation, Newton,
Mass., a corporation of Massachusetts

Application May 2, 1942, Serial No. 106,775

Term of patent 14 years

To all whom it may concern:

Be it known that I, Ruth E. Gutfrucht, a citizen of the United States residing at Rochester, in the county of Monroe and State of New York, have invented a new, original, and ornamental Design for Embossed Paper for Paper Napkins or Similar Articles, of which the following is a specification, reference being had to the accompanying drawing forming part thereof.

The figure is a plan view of embossed paper for paper napkins or similar articles embodying my new design.

I claim:

The ornamental design for embossed paper for paper napkins or similar articles, substantially as shown.

RUTH E. GUTFRUCHT.
